UNITED STATES PATENT OFFICE.

SAMUEL SAMBOR, OF NEWARK, NEW JERSEY.

MACHINE FOR DISPENSING ARTICLES.

Application filed September 11, 1926. Serial No. 134,763.

This invention relates to an improved machine for dispensing articles and is designed particularly for such articles as are sold by number, the machine being slow enough to permit a counting of the articles and is designed to prevent the necessity of handling them.

The invention is also designed to provide a display means so that the articles in bulk 10 form an attraction and the machine is therefore particularly adapted for sale and dispensing of rolls, buns, and similar edible articles in which the prime necessity is to prevent the customers from handling the 15 goods but to enable them to count out and deliver the required number.

The invention is illustrated in the accompanying drawings in which Figure 1 is a side view and Figure 2 is a front view of a 20 machine embodying my invention. Figure 3 is a section on line 3—3 in Figure 2. Figure 4 is a section on line 4—4 in Figure 3. Figure 5 is a top view of the machine and Figure 6 is a perspective view of a plunger 25 for selecting the articles.

The device comprises a casing which is usually designed as a store fixture having a lower part 10 which functions as a stand or support and an upper part 11 which is preferably made up to provide a display fixture and I show one comprising the standards 12 supporting the glass sides 13. This upper 30 or display portion has a top which has an opening 14 through which the articles can be deposited into the structure, a lid 15 being normally used to close the top to keep the dust out. The bottom part of the upper portion has inclined panels 16 to direct the articles to be dispensed toward a selected 35 point toward the bottom, usually the centre.

At that point, I provide a guide 17 in which is fitted a plunger 18 which is reciprocated up and down by a suitable mechanism, when it is down the plunger forming a part of the bottom and when it is up the plunger supporting a single article which is automatically swept from the top of the plunger through a delivery opening.

In the form shown the mechanism for operating the plunger comprises a cross head

19 on the plunger, said cross head having a slot 20 in which the pin 21 of the fly wheel 22 projects. The fly wheel 22 is mounted on a shaft 23 which can be driven by means of a pulley 24 and the belt 25 and the pulley 26. The pulley 26 can be turned by a handle 27. In some cases this manual means can be disbanded. The wheel 22 can be turned by means of the belt 28 which transmits motion to the shaft 22 from the motor 29. Suitable 55 wiring, of course, is involved to enable the machine to be started and stopped and I show as typifying such conveniences a switch 30.

In order to sweep an article from the 60 plunger when the plunger is raised, I arrange a paddle 31 which I illustrate as at 32 and which normally rests in the position shown in Figures 1 and 3, either held in normal position by a spring or by the influence of a weight 33. This paddle is tripped and the plunger rises to its raised position and I show a rod 34 which engages the part 33 or any portion of the paddle above its pivot so that the paddle is swung 75 to the position shown at 35 in Figure 3. Opposite the upper position are the top of the plunger and the delivery opening which is usually in the form of a chute 36 at the end of which is a receiver such as a paper bag 80 which is held to receive the rolls or other articles.

In using the apparatus the rolls are deposited in the top and are on display through the glass sides and when they are 85 to be dispensed, the operating means such as the handle 27 is rotated which causes the plunger to reciprocate, the top of the plunger being in proportion so that it holds but one article.

The article is carried upward through the mass and as it arrives opposite the delivery chute, the paddle 31 is tripped by the rod 34 and the article is delivered through the chute 36. The operation of the apparatus 95 is slow enough to permit easy counting and at the same time make it more sanitary and also quicker to count and place in a bag or the like the required number.

It will be evident that various modifica-

tions can be devised for carrying out the operation without departing from the scope of the invention.

I claim:

5. A dispensing apparatus comprising a holder with an inclined bottom, a vertically movable plunger forming the bottom of the holder at the foot of the incline, means for reciprocating the plunger, a paddle pivoted

to the holder above the plunger and adapted to be swept across the top of the plunger, the paddle having a pivoted connection and an inclined face above said connection, and a rod on the plunger to engage said face to move the paddle.

10. In testimony whereof I affix my signature.

15

SAMUEL SAMBOR.
